PROCESS FOR REMOVING MERCAPTANS
FROM MINERAL OILSWalter H. Rupp, Mountainside, N. J., assignor to
Standard Oil Development Company, a corpora-
tion of Delaware

Application August 16, 1950, Serial No. 179,812

6 Claims. (Cl. 196—32)

1

The present invention is concerned with the refining of mineral oils and is more particularly concerned with the removal of mercaptan compounds from naphthas from catalytic cracking.

Naphthas obtained by the catalytic cracking of hydrocarbons contain unstable aromatic mercaptans and diolefins which react to form undesirable gums and resins when the naphtha is exposed to air or prolonged heating.

It is known to remove these mercaptans by treatment with caustic soda. However, the naphtha fractions so treated often contain considerable quantities of hydrogen sulfide and carbon dioxide with the result that caustic consumption is excessive. In order to avoid excessive caustic consumption it has been proposed to separate a well fractionated light side stream from the catalytic naphtha, strip it to specification boiling point and wash this cut with caustic. This process, however, has the disadvantage that the absence of the heavy naphtha increases gas production by reducing the mols of liquid in equilibrium with the gases vented from the top of the tower. This increases compression and installation costs for handling the additional gases.

In accordance with the present invention the above disadvantages are overcome by separating the naphtha into a light overhead cut boiling up to about 250° F. containing most of the hydrogen sulfide and carbon dioxide and a rough side cut boiling between about 250 and about 400° F. containing 1-5% of the hydrogen sulfide. The rough cut naphtha contains the aromatic mercaptans boiling about 300° F. and higher. This is cooled and washed with .01 to 0.2 volume of caustic per volume of rough cut naphtha, preferably in a countercurrent contactor, at 80°-150° F. The contactor is of conventional type having either perforated plates, packing or other contacting devices. The washed naphtha is then injected into the overhead condenser inlet line and remixed with the light naphtha and gas fractions. By so doing, the low pressure gas volume is held to a minimum and is unchanged from normal operating procedures.

For a further understanding of the invention, reference may be had to the accompanying drawing in which the single figure is an elevational view, generally diagrammatic, showing an apparatus embodying the improvement of the present invention.

Referring now to this drawing, the total effluent from a catalytic cracking reaction zone is introduced by line 1 to the lower part of fractionating zone 2 when it is subjected to the usual distilla-

2

tion and fractionating processing to give a light overhead, and naphtha and gas oil side cuts.

According to the present invention, all fractions boiling below 250° F. and taken overhead through line 3, and condensed in condenser 4. The liquid and gas from condenser 4 are passed to separator 5 from which low pressure gas is removed through line 6 and low pressure distillate through line 7. A further feature of the invention involves the removal of a rough fraction boiling from about 250° F. up to about 400° F. through line 8. This fraction is cooled in cooler 9 and a portion thereof may be returned as reflux through line 10. The remainder of this fraction is passed to contacting zone 11 where it is passed countercurrent to a caustic soda solution of 5% to 20% strength introduced through line 13 at a temperature between 80° and 150° F. A treat of 1-5% of caustic by volume on naphtha usually suffices for removing the aromatic mercaptans. In this operation the caustic removes the troublesome aromatic mercaptans from the roughly fractionated naphtha. Since most of the gas and acidic components have been removed from this fraction the caustic requirements are materially lowered. The washed naphtha is then passed by line 12 to condenser 4 where it is mixed with the overhead condensate. By operating in this manner the heavy naphtha is recombined with the gas and acts to dissolve large portions of it in the low pressure distillate thus avoiding overloading the low pressure compressors in subsequent processing. The spent caustic is removed from contactor 11 through line 14 and passed to the sewer or to mercaptan recovery units.

The nature and objects of the present invention having been thus described and illustrated, what is claimed as new and useful and is desired to be secured by Letters Patent is:

1. Process for treating a catalytically cracked mixture of hydrocarbons boiling in the naphtha range which comprises fractionally distilling said mixture to form an overhead vapor fraction boiling up to about 250° F., removing a second fraction boiling in the range of about 250° F. to 400° F., caustic washing said second fraction, combining the overhead vapor and the caustic washed fraction, thereafter condensing at least a portion of the said vapor fraction while in admixture and contact with the said caustic washed fraction.
2. Process as described in claim 1 in which the side stream fraction is caustic washed with between .01 and 0.2 volume of caustic per volume of side stream.
3. Process as described in claim 1 in which the

side stream is caustic treated at a temperature between about 80° F. and 150° F.

4. Process for removing mercaptans from the products of a catalytic cracking operation which comprises fractionally distilling said products in a distillation column to form various boiling range fractions, removing a first fraction boiling up to about 250° F. overhead as a vapor, removing a second fraction boiling roughly between 250° F. and 400° F. as a side stream, cooling said side stream, caustic washing the cooled side stream, combining the overhead vapor and the caustic washed fraction, thereafter condensing at least a portion of the said vapor fraction while in admixture and contact with the said caustic washed fraction.

5. Process as in claim 4 in which a part of the cooled side stream is returned to the distillation column as reflux.

6. Process as in claim 4 in which the cooled side stream is caustic washed with between .01 and 0.2 volume of caustic per volume of side stream at a temperature between 80° F. and 150° F.
